UNITED STATES PATENT OFFICE.

ALBERT F. SAUNDERS, OF SYRACUSE, NEW YORK, ASSIGNOR TO L. N. BENEDICT MFG. CO., OF EAST SYRACUSE, NEW YORK.

DESIGN FOR A SODA-GLASS HOLDER.

Application filed February 5, 1925. Serial No. 12,274. Term of patent 3½ years.

To all whom it may concern:

Be it known that I, ALBERT F. SAUNDERS, a citizen of the United States, residing at 106 Rugby Road, city of Syracuse, county of Onondaga, and State of New York, have invented a new, original, and ornamental Design for a Soda-Glass Holder, of which the following is a specification, reference being had to the accompanying drawing, forming a part thereof, wherein—

Figure 1 is a side elevation of the soda glass holder.

Figure 2 is a top plan view of the soda glass holder.

I claim:

The ornamental design for a soda glass holder, substantially as shown.

In testimony whereof, I have hereunto signed my name at East Syracuse in the county of Onondaga and State of New York, the 2nd day of February, 1925.

ALBERT F. SAUNDERS.
